FRAME FOR SHIFFLI EMBROIDERY MACHINES

Abraham Eskin, Brooklyn, N. Y.

Application March 30, 1939, Serial No. 264,893

6 Claims. (Cl. 112—90)

This invention relates to new and useful improvements in a frame for Shiffli embroidery machines.

The invention has for an object the provision of 5 a novel arrangement of bars, angle irons, rods and bolts arranged in a manner so that the material or garment to be embroidered may be stretched upon the frame and thereafter further stretched so as to assure that it maintains a 10 taut position.

Still further the invention proposes to characterize the stretching arrangement by an angle member adapted to be clamped down upon portions of the material or garment, and a rod for 15 each angle member swivelly mounted to move laterally towards the angle member and arranged to provide the additional stretch required.

Still further the invention contemplates the use of a novel bolt for locking each pair of angle 20 members and its associated rod in an operative position.

For further comprehension of the invention, and of the objects and advantages thereof, reference will be had to the following description and 25 accompanying drawings, and to the appended claims in which the various novel features of the invention are more particularly set forth.

In the accompanying drawings forming a material part of this disclosure:

30 Fig. 1 is a plan view of a Shiffli embroidery machine frame constructed according to this invention.

Fig. 2 is a perspective view of Fig. 1.

Fig. 3 is a fragmentary enlarged vertical sectional view taken on the line 3—3 of Fig. 1.

Fig. 4 is a fragmentary plan view looking in the direction of the line 4—4 of Fig. 3.

Fig. 5 is a fragmentary sectional view taken on the line 5—5 of Fig. 1.

Fig. 6 is a view similar to Fig. 5 but illustrating the parts thereof in a different position.

Fig. 7 is a fragmentary perspective view of a portion of Fig. 1 looking in the direction of the line 7—7 thereof.

Fig. 8 is another view similar to Fig. 5 but illustrating separate garments clamped in the device.

The frame for Shiffli embroidery machines, according to this invention, includes a pair of 50 spaced parallel side arms 10 and 11, and a plurality of parallel spaced bars 12 mounted between said arms and each bar being of curved, channel shape (see Figs. 5 and 6) in transverse cross section with one of the sides 12^a of the channel shape narrower than the other side, and this

narrower side being provided with an outwardly extending flange 12^b. An angle member 13 is provided for each bar 12 and is hingedly mounted at one of its ends by a bolt 14 upon the said bar 12 and is movable to have one of its sides, the side 13^a (see Figs. 5 and 6) engage in the channel shape of the bar 12 and the other of its sides, namely the side 13^b, to extend over the flange 12^b. A rod 15 is provided for each of the flanges 12^b, and said rod is pivotally mounted thereon by a pintle rivet 16, and is arranged to be movable to a position between the flange and the adjacent side 13^b of the angle member. This rod 15 is preferably curved and elastic, and made of tempered steel.

The side arm 10 is an angle member. The side arm 11 also is an angle member, and these angle members have their rear legs in a common plane with their other legs remote from each other and extending in the same direction. The bars 12 are secured to the adjacent legs of the side arms 10 and 11 by several rivets 17 so that the side arms and the bars 12 are connected together as a rigid unit.

The pivoted end of each angle member 13 has 25 a cutout area 13^c immediately adjacent the pivot end thereof. This area is cutout from one of the legs of the angle member so that the other leg of the angle member (see Fig. 4) is free, see the portion 13^d. It is through this portion 13^d that 30 the pintle rivet 16 is mounted. This pintle rivet 16 also engages through the wide arm of the channel shaped bar 12. The pintle rivet 16 engages through the rod 15, then passes through the flange 12^b, then passes through a spacer tube 35 19, and then through the material of the side arm 10. A friction element, such as a tube of felt material or similar material 20, is mounted upon each of the rods 15 preferably at an intermediate area. This tube 20 extends from a short distance from one end of the rod to a short distance 40 of the other end of the rod, in this respect see Fig. 2.

Each angle member 13 and rod 15 is provided with a locking bolt of novel design. There is a 45 loop element 21 secured by several rivets 22 to one of the legs of the side member 11. A bolt 23 slidably engages through the loop 21. This bolt has a handle portion 23^a by which it may be turned and moved longitudinally. The other end 50 of the bolt 23 is provided with a hook portion 23^b. The bolt 23 is adapted to be moved over one leg of the angle member 13 to lock the angle member in position. This end of the angle member 13 is cutout at 13^c to clear the adjacent edge of 55

the leg of the side member 11. After the rod 15 is moved laterally into position between the angle member 13 and the flange 12^b, the bolt 23 may be turned to move the hook end 23^b across the 5 edge of the rod 15 to lock this rod in position. Several spring clamps 25 are mounted upon the side arm 10 and are adapted to support sheet material 26 to be embroidered. This material may be in the form of a garment, or piece goods, 10 or a sheet of fabric of any size and material.

The operation of the device is as follows:

First the bars 15 are swung to their open positions which comprise laterally extended positions, one such position being indicated by dot and dash 15 lines in Fig. 2. Then the angle members 13 are swung upwards to their open positions. The cloth material or garment 26 is engaged by the clamps 25 to support one of its sides. The other side of the cloth material is pulled to make it 20 taut and the first angle member 13 is pivoted downwards to force an area of the cloth material or garment into the channel shaped bar 12, and clamp it in position, as shown in Figs. 5 and 8. Then the cloth or garment is pulled taut laterally and the next angle member 13 is pivoted 25 down to stretch the area between the angle members as shown in Fig. 5. In this manner each of the angle members 13 are moved down to their clamping position. These angle members are 30 held in their clamping positions by the bolts 23 which are pushed laterally across the top sides of the angle members. The excess portion of the cloth or garment hangs down on the right hand side of the clamps.

35 A close inspection of Fig. 5 will show that the rods 15 are in inoperative positions with the web of the material above them, disposed at an inclination. The rods 15 are then pivoted laterally from the positions indicated in Fig. 5, to the 40 positions shown in Fig. 6. This will force the webs of material off the flanges 12^b, since the rods engage into these areas. This causes extra stretching of the cloth webs or garment. In this manner the necessary additional tension is obtained in a very simple manner and both ends of 45 garment remain on one side as shown on Fig. 8. The rods 15 are held in their operative positions by turning the bolts 23 so that the hook ends 23^b engage over the edges of the rods 15 holding them in locking positions.

50 It is to be understood that the excess parts may also be made to hang on the left hand side of the clamping device, by making the clamping arrangement swingable toward the left, instead of the right direction.

55 While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

60 1. In a frame for Shiffli embroidery machines, a pair of spaced parallel side arms, a plurality of parallel spaced bars mounted between said arms and each bar being of channel shape in cross section with one of the sides of the channel shape narrower than the other and having an outwardly extending flange, an angle member for each bar and hingedly mounted thereon and movable to have one of its legs engage in the channel 65 shape and the other of its legs extend over said 70

flange, a rod for each of said flanges pivotally mounted thereon and movable to a position between the flange and the adjacent leg of the angle member, a bolt for each angle member and rod and slidably mounted on one of said side arms for extending over the angle member and having a hooked end engageable over the rod when the bolt is turned.

2. In a frame for Shiffli embroidery machines, a pair of spaced parallel side arms, a plurality of parallel spaced bars mounted between said arms and each bar being of channel shape in cross section with one of the sides of the channel shape narrower than the other and having an outwardly extending flange, an angle member for each bar and hingedly mounted thereon and movable to have one of its legs engage in the channel shape and the other of its legs extend over said flange, a rod for each of said flanges pivotally mounted thereon and movable to a position between the flange and the adjacent leg of the angle member, a bolt for each angle member and rod and slidably mounted on one of said side arms for extending over the angle member and having a hooked end engageable over the rod when the bolt is turned, said side arms comprising angle members having one of their legs in a common plane and their other legs opposed to each other.

3. In a frame for Shiffli embroidery machines, a pair of spaced parallel side arms, a plurality of parallel spaced bars mounted between said arms and each bar being of channel shape in cross section with one of the sides of the channel shape narrower than the other and having an outwardly extending flange, an angle member for each bar and hingedly mounted thereon and movable to have one of its legs engage in the channel shape and the other of its legs extend over said flange, a rod for each of said flanges pivotally mounted thereon and movable to a position between the flange and the adjacent leg of the angle member, a bolt for each angle member and rod and slidably mounted on one of said side arms for extending over the angle member and having a hooked end engageable over the rod when the bolt is turned, said side arms comprising angle members having one of their legs in a common plane and their other legs opposed to each other, said spaced bars being disposed between the opposed legs of said side arms and being fixedly connected with the other legs of said side arms.

4. In a frame for Shiffli embroidery machines, a pair of spaced parallel side arms, a plurality of parallel spaced bars mounted between said arms and each bar being of channel shape in cross section with one of the sides of the channel shape narrower than the other and having an outwardly extending flange, an angle member for each bar and hingedly mounted thereon and movable to have one of its legs engage in the channel shape and the other of its legs extend over said flange, a rod for each of said flanges pivotally mounted thereon and movable to a position between the flange and the adjacent leg of the angle member, a bolt for each angle member and rod and slidably mounted on one of said side arms for extending over the angle member and having a hooked end engageable over the rod when the bolt is turned, end portions of said angle members being cut away to expose the pivots of the angle members and to project the remote tips of the angle members to positions over which said bolts may engage.

5. In a frame for Shiffli embroidery machines, a pair of spaced parallel side arms, a plurality of parallel spaced bars mounted between said arms and each bar being of channel shape in cross section with one of the sides of the channel shape narrower than the other and having an outwardly extending flange, an angle member for each bar and hingedly mounted thereon and movable to have one of its legs engage in the channel shape and the other of its legs extend over said flange, a rod for each of said flanges pivotally mounted thereon and movable to a position between the flange and the adjacent leg of the angle member, a bolt for each 10 angle member and rod and slidably mounted on one of said side arms for extending over the angle member and having a hooked end engageable over the rod when the bolt is turned, each of said rods being provided with a friction covering material.
- 15 6. In a frame for Shiffli embroidery machines, a pair of spaced parallel side arms, a plurality

of parallel spaced bars mounted between said arms and each bar being of channel shape in cross section with one of the sides of the channel shape narrower than the other and having an outwardly extending flange, an angle member for each bar and hingedly mounted thereon and movable to have one of its legs engage in the channel shape and the other of its legs extend over said flange, a rod for each of said flanges pivotally mounted thereon and movable to a position between the flange and the adjacent leg of the angle member, a bolt for each angle member and rod and slidably mounted on one of said side arms for extending over the angle member and having a hooked end engageable over the rod when the bolt is turned, end of said bolts being slidably mounted in a loop member fixed on said frame, and each bolt having a handle by which it may be turned so that the hooked end engages over the rod as specified.
